United States Patent

Des. 239,805
Patented May 11, 1976

239,805

SUPERMARKET PRODUCE DISPLAY FIXTURE

Louis E. South, Kansas City, Mo., assignor to The Weather Box Company, Kansas City, Mo.

Filed Mar. 26, 1975, Ser. No. 562,343

Term of patent 14 years

Int. Cl. D20—02

U.S. Cl. D6—187

Fig. 1.

Fig. 2.

Fig. 3.

FIG. 1 is an enlarged perspective view of a supermarket produce display fixture showing my new design;

FIG. 2 is a front elevational view thereof; and

FIG. 3 is a side elevational view thereof, showing the side opposite that shown in FIG. 1.

The top and back of the supermarket produce display fixture are plain.

I claim:

The ornamental design for a supermarket produce display fixture, as shown and described.
